The ornamental design for vehicle headlight, as shown and described.

DESCRIPTION

FIG. 1 is a front perspective view of vehicle headlight, showing our design.

FIG. 2 is a bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the vehicle headlight that form no part of the claimed design.
